UNITED STATES PATENT OFFICE.

OLIVER H. ARNO, OF WILMINGTON, ASSIGNOR TO AMERICAN AUTOMATIC ORGAN COMPANY, OF BOSTON, MASSACHUSETTS.

MECHANICAL MUSICAL INSTRUMENT.

SPECIFICATION forming part of Letters Patent No. 233,721, dated October 26, 1880.

Application filed June 18, 1880. (No model.) Patented in England May 26, 1880.

To all whom it may concern:—

Be it known that I, OLIVER H. ARNO, of 5
Wilmington, in the county of Middlesex and
State of Massachusetts, have invented certain
new and useful Improvements in Mechanical
5 Musical Instruments, of which the following is
a full, clear, and exact description.

This invention pertains to that class of 10
mechanical musical instruments arranged by the
passage of a perforated paper strip to secure
the automatic playing of the instrument in
accordance with the disposition of the perfor-
15 ated and unperforated portions of the paper
strip in relation to each other, and to the
mechanism for opening and closing the reed-
valve, &c.

In a patent granted to me May 18, 1880,
and numbered 227,714, the perforated strip is
provided with two lines of perforations, the
20 perforations of one line being for opening, and
the perforations of the other line being for
closing, a sliding valve through the medium of
two separate levers.

The object of my present invention is to dis-
25 pense with the line of perforations for closing
the sliding valve, and also to open or close said
valve by means of a single lever.

The invention consists of a reed-valve ar-
ranged to slide to open and close the reed, and
30 of a lever connected to the valve, and con-
structed and otherwise arranged and dis-
posed in such relation thereto and to the rows
of perforations in the paper strip which cor-
35 respond to such reed that in the passage of
the perforated and unperforated portions of
the perforated strip by a given point the lever
opens the valve at the passage of each perfor-
40 ated portion, and so keeps it open for the
length of such perforation, and closes the valve
45 at the passage of such unperforated portion,
and so keeps it closed for the length of such
unperforated portion, all substantially as here-
inafter described.

In the accompanying plate of drawings my
45 invention is illustrated, Figures 1 and 2 be-
ing vertical sections in the line of travel of
the perforated strip, the one showing the valve
as closed and the other as opened.

In the drawings, A represents a horizontal

bed or raceway. Along this bed and under a 50
cross-block, B, the perforated strip of paper
C passes, suitable mechanism—such as feed-
rolls—being employed to secure the continuous
passage of the paper strip.

The paper strip C is provided with a series 55
of parallel rows of perforations, and each row
runs in the line of travel of the strip through
the raceway. In line with each row of per-
forations there is an opening, e, in the race-
way, and block B and a horizontal lever, D, 60
below the raceway A.

Each horizontal lever D, at its one end, e,
is hung to a fulcrum-pin, a, and near its other
end, f, it has on its upper side a wedge-piece,
b, suitably located to enter the opening e in 65
the raceway and block in line with it.

E is a bent spring placed below each lever.
This spring at one end is fastened to a block,
d, and at the other end it presses upwardly
against the under side of its lever. 70

F is a vertical arm attached to each lever,
and at its lower end hinged to a reed-valve, G,
arranged to slide horizontally over the face of
the reed-chamber H. When this valve is slid
in one direction the reed-valve is opened, and 75
when it is slid in the other direction the valve
is closed, and the arrangement of each valve
and its lever-connection described is such
that the downward swing of the lever closes,
and the upward swing of the lever opens, the 80
valve.

The opening of the valve is against the
pressure of the spring, and its closing is with
such pressure.

As each lever is arranged in the travel of 85
the perforated strip C through the raceway,
it opens its valve and holds it open, when a
perforated portion of the paper strip is pass-
ing by its wedge-piece b, and it closes its valve
and holds it closed when an unperforated por- 90
tion of the paper strip is passing by its wedge-
piece b, all as is plain without further de-
scription.

Having thus described my invention, what
I claim, and desire to secure by Letters Pat- 95
ent, is—

In a mechanical musical instrument in which
a perforated strip, C, is employed, the combi-

nation of slide-valve G with the single lever D, arranged and connected together, and in relation to the perforated and unperforated portions of the strip C, substantially in the 5 manner described, whereby the said slide-valve is both opened and closed by the single lever D, as set forth.

In testimony whereof I have hereunto set my hand in the presence of two subscribing witnesses.

OLIVER H. ARNO.
